CARRYING BAG

Irene M. Murray, Weehawken, N. J., assignor to Talon, Inc., a corporation of Pennsylvania

Application April 5, 1952, Serial No. 19,203

Term of patent 14 years

(Cl. D87—5)

To all whom it may concern:

Be it known that I, Irene M. Murray, a citizen of the United States, residing at Weehawken, in the county of Hudson and State of New Jersey, have invented a new, original, and ornamental Design for a Carrying Bag, of which the following is a specification, reference being had to the accompanying drawing, forming a part thereof.

In the drawing:

Fig. 1 is a side elevational view of a carrying bag showing my new design;

Fig. 2 is a side elevational view of another side of the bag showing the opening thereinto; and

Fig. 3 is a top view of the same.

I claim:

The ornamental design for a carrying bag, substantially as shown.

IRENE M. MURRAY.
